CLAIM

The ornamental design for a display screen or portion
thereof with graphical user interface as shown and
described.

DESCRIPTION

The FIGURE is a front view of a display screen or portion
thereof with graphical user interface according to the
claimed design.

The dash-dot-dash broken lines in the drawings illustrate
boundaries of the display screen or portion thereof that form
no part of the claimed design.

The dash-dash broken lines in the drawings illustrate portions
of the graphical user interface that form no part of the
claimed design.

In the FIGURE, the first hatch shading is shown at the left
group in the upper, first viewport, the upper group in the
lower, second viewport, and the upper, first group indicator
at the left side of the graphical user interface. The second
hatch shading is shown at the right group in the upper, first
viewport, the lower group in the lower, second viewport, and
the lower, second group indicator at the left side of the
graphical user interface. The first hatch shading and the
second hatch shading represent contrast in appearance,
although no particular colors are claimed. Additionally, the
heavier line weight of the first hatch shading represents
higher opacity relative to the lower line weight of the second
hatch shading. Any pattern formed by any of the hatch
shading forms no part of the claimed design.
